UNITED STATES PATENT OFFICE

ROBERT R. PAGE, OF NEW YORK, N. Y.

MUTE FOR STRINGED MUSICAL INSTRUMENTS

Application filed June 14, 1929. Serial No. 370,987.

Our present invention relates to stringed musical instruments and has for its principal object an improvement in mutes therefor.

The mute herein is intended for use with bridged musical instruments such as violins, banjos, ukuleles, and the like although as disclosed herein it is applied to a characteristic banjo structure.

One of the objects of the present device is to provide a mute which is carried upon the tailpiece of a stringed instrument, such tailpiece being suitably modified to permit the mute to be movably carried thereon in close association with the string bridge of such instrument, whereby it may be manually and quickly moved into and out of muting contact with said bridge to modify the tone qualities of the instrument.

Another object is to mount the mute so that it is firmly located when out of muting position under or near one hand of the player for such instant manipulation as may be desired.

Another object is to insure that the mute, when in muting contact with the bridge of the instrument, is in firm contact so that the muting or damping action of the bridge-engaged mute is substantially free of mechanical restraint and enabled to exercise such control of the vibrations of the sounding portion of the instrument as to permit a carrying or sustained resonance thereof.

Another object is to provide a mute which may be carried upon a tail piece as above described, which coacts with said tail piece and interassociate guiding means therebetween whereby the mute may be instantly and accurately guided into a firm muting engagement with the bridge of the instrument.

Another object is to provide a mute wherein the bridge-contactive faces are of a tapering nature whereby to firmly engage the mute in a non-slipping wedging engagement.

These and other objects will be apprehended as the description proceeds and it is obvious that modifications may be made without departing from the spirit hereof or the scope of the claims.

Referring to the drawings,

Fig. 1 is a fragmentary plan view of a

stringed instrument illustrating the mute in contact with the bridge in full lines and in normal position out of engagement with the bridge indicated by the dotted lines.

Fig. 2 is a sectional view taken on the line 2-2 of Fig. 1 in the direction of the arrows showing the mute engaging the bridge. 55

Fig. 3 is a sectional view taken on the line 2-2, Fig. 1, in the direction of the arrows with the muting member removed. 60

Fig. 4 is a transverse view in elevation of the muting member.

Fig. 5 is a bottom view in perspective of the muting member.

Fig. 6 is a fragmentary plan view of a string instrument illustrating a modified muting member contacting the sides of the bridge. 65

Fig. 7 is a view taken on line 7-7 Fig. 6, in the direction of the arrows. 70

In the drawings 10 designates a wooden banjo rim suitably securing the spacing plate frame 11 carrying the annular frame band 12. The plate frame 11 is provided with groove 13 comprising a seat to which is preferably 75 secured the tone ring 14 and disposed over the latter and in contact therewith is the diaphragm or vellum 15 which is stretched taut and extended over the upper portion of frame band 12 and downwardly engaging the outer face thereof terminating in a hollow bead 16 or reflexed portion in which is mounted the flesh ring 17.

The strain ring 18 suitably holds the diaphragm 15 against the frame band 12 and 85 bead 16 against the flesh ring. The above described structure is adapted for any stringed instrument, but as illustrated in the drawings, forms the foundation for one form of a banjo, but it is to be understood that it may be applied to other forms of banjos and to ukuleles, mandolins or the like. 90

Extending over diaphragm 15 and in spaced relation therewith is the cantilever tail piece member 19 comprising an elongated plate preferably of flat metal, including the flared enlarged portion 20 merging into a narrow, resilient guide arm 21, which extends radially of the banjo and projects into the cut away portion or opening 22 be- 100

tween the feet of a string supporting bridge 23 and beyond the bridge terminating in the free portion 24.

The enlarged flared portion 20 is provided with an integral downwardly depending flange 25 abutting the strain ring 18 and is preferably fastened to the frame band 12 by means of suitable studs 26.

Preferably fastened to the tail piece 19 on the arm 21 is the flat strip spring tongue 27 which is secured to arm 21 by rivets or screws 28. Tongue 27 extends longitudinally of arm 21 and extends towards the bridge 23 and away from the arm due to its resiliency projecting through bridge opening 23 over the free portion 24 and in spaced relation thereto.

The downwardly depending flange 25 is provided with a plurality of spaced slotted members 29 for securing the knotted end of the banjo strings 30 which extend over diaphragm 15 being supported in the spaced grooves 31 on bridge member 23.

The mute generally denoted by 32 comprises a body 33, preferably of wood, having a downwardly sloping top face 34 to which is secured a mute encompassing metal plate 35 embodying the tapering, arcuately disposed integral wings or sides 36 (see Fig. 5) which are curved to snugly embrace the chamfered or curved sides 37 and underfaces 38 of the underface of mute body 33. These underfaces 38 are formed by cutting a longitudinal tail piece guide channel co-extensive of the length of mute 33 to form a sliding guide way 39 to fit upon the tail piece extension 24.

The curved wings 37 terminate into longitudinal marginal reflexed portions 39' bearing snugly against the adjacent outer margins of each ledge 38 thereby providing a firm connection for the body 33 with the metal plate 35 without employing any independent fastening means.

The guide channel 39 is bridged over by the transverse metal strap or guide plate 40 fastened to the underfaces 38 by rivets 41 or the like.

Secured adjacent the rear end of the mute is the accessible and manipulatable post 42 which is attached to the mute by a screw 43 countersunk in the web 38' and extending through the metal plate 35. It will be noted that the front or tapering nose portion 44 of the mute is rounded as at 45 and is thinner than the rear end of the mute thereby to form an inclined wedge face to be easily wedged between the inside of the feet forming the opening 22 in bridge 23.

In use, the spring pressure tongue 27 and arm 21 of the tail piece are passed into the guide channel 39 and between the strap or guide plate 40 in such manner that the tongue 27 and arm 21 extend longitudinally through guide channel 39.

Normally, the mute is in the position shown by the dotted lines in Fig. 1, that is, in non-

muting relation upon the tail piece and out of contact with the bridge and when it is desired to modulate the tone of the instrument, the mute is moved by manually actuating member 42 to slide the wedge face of the mute into engagement into the opening 22 of the bridge. The stud 42 is arranged between the center strings, that is between the second and third strings but in no way contacts the latter. Thus, it follows that the mute can be quickly slid into and out of muting engagement with the bridge.

When the mute member is out of contact with the bridge, it is maintained in such inoperative position by the pressure of the spring tongue 27 in the guide channel 39.

When the mute is wedged against the bridge in muting contact therewith, owing to the length and resiliency of the tail piece guide extension arm 21, the rigid engagement of the mute with the bridge causes the vibrations of the resonating part of the instrument to be damped, without, however, breaking down the sustained, vibratory tone frequencies. They are damped, but not shortened in vibrating periods.

In the embodiment disclosed in Figs. 6 and 7, the mute 50 is substantially identical in construction with the species disclosed in Figs. 1 to 5 inclusive, the exception being that the mute is forked embodying the laterally extending forwardly projecting arms 51 and 52 including the inwardly disposed muting faces 53 and 54 respectively adapted to engage the external end faces 55 and 56 of bridge 23 for muting the instrument.

The tongue 59 and tail piece extension 60 are guided between strap 61 and the guide channel 62 whereby the mute may be moved into and out of engagement with the bridge by the stud 63, and thus be directed either into muting engagement with or away from the bridge, as will be apparent.

Thus, it will be noted that I have provided a mute that may be carried permanently upon the desired instrument, without interference with the normal full tone thereof, but which may by a slight manual movement, be engaged or disengaged with the bridge thereof, and which mute while carried by the bridge in such muting engagement is freely controlled to coact with the bridge-supporting diaphragm of such instrument. Thus while the mute modifies the tone of such instrument it does not in any way destroy the sustention of the tone vibration thereof.

Having thus described our invention, what we claim is:

1. In a stringed musical instrument, having thereon a bridge, a tail piece having thereon an extension, a mute body having thereon a tapered part slidably mounted on said extension, a means for sliding said body on said extension with said part thereof into wedging engagement with said bridge and a

means for normally holding said body on said extension in nonmuting position with said part thereon out of engagement with said bridge.

whereby said body may be retained by said tongue in position on said extension when said body is in unmuting position.

- 5 2. In a stringed musical instrument a tail piece, having thereon an extension, a bridge and a mute body, having thereon a tapered part, slidably mounted on said extension and disposed to be slid on said extension with said 10 part thereof into wedging engagement with the underside of said bridge, thereby muting the instrument.

10. In a stringed musical instrument having thereon a bridge, a tail piece having thereon an extension, a mute body having thereon a tapered part slidably mounted on said extension, a means for sliding said body on said extension with said part thereof into wedging engagement with said bridge and a means for normally holding said body on said extension in non-muting position with said part thereon out of engagement with said bridge, a resilient means disposed to react at one end thereof on said extension and at the other end thereof on said body whereby to retain said body on said extension with said part thereof in wedging engagement with said bridge when said body is in muting position, said body having thereon a member to act as an abutment for said extension whereby said body may be retained by said resilient means in position on said extension when said body is in unmuting position.

- 15 3. The elements of claim 1, combined with a resilient tongue on said extension for retaining said body with said part thereof in resilient wedging engagement with said bridge when said body is in muting position.

15. Signed at New York in the county of New York and State of New York this 12th day of June, A. D. 1929.

ROBERT R. PAGE.

4. The elements of claim 1, said body having thereon longitudinally extending tapered 20 arms, having thereon inwardly disposed tapered muting faces, to wedgingly engage the end faces of said bridge.

20. 5. The elements of claim 1, said body having thereon at the underside thereof a longitudinally disposed guide channel to fit said extension, whereby to guide said body in its sliding motion on said extension into and out of muting position.

- 25 6. The elements of claim 1, combined with a resilient means, disposed to react at one end thereof on said extension and at the other end thereof on said body, whereby to retain said body on said extension with said part thereof in wedging engagement with said bridge when said body is in muting position.

25. 100

7. The elements of claim 1, said body comprising a wooden base and a metal plate encompassing the same, said plate having thereon arcuately disposed integral wings curved 40 to snugly embrace the sides of said base, thereby securing the latter to said plate.

40. 105

8. The elements of claim 1, said body having thereon underfaces, extending to the underside of said extension and said body 45 having thereon a guide plate, fastened at the underside of said guide faces, to form a bridge over said extension, thereby retaining said body on said extension against any upwardly acting force tending to lift the same.

45. 110

- 50 9. In a stringed musical instrument having thereon a bridge, a tail piece having thereon an extension, a mute body having thereon a tapered part slidably mounted on said extension, a means for sliding said body on said extension with said part thereof into wedging engagement with said bridge, a means for normally holding said body on said extension in non-muting position with said part thereon out of engagement with said bridge, a resil-
